UNITED STATES PATENT OFFICE.

SARAH J. ROOT, OF NEW HAVEN, CONNECTICUT.

LOCKING DEVICE FOR FASTENING DEVICES OF CORSETS.

SPECIFICATION forming part of Letters Patent No. 534,760, dated February 26, 1895.

Application filed August 16, 1894. Serial No. 520,441. (No model.)

To all whom it may concern:

Be it known that I, SARAH J. ROOT, of New Haven, in the county of New Haven and State of Connecticut, have invented a new Improvement 5 in Locking Devices for the Fastening Devices of Corsets; and I do hereby declare the following, when taken in connection with the accompanying drawings and the letters of reference marked thereon, to be a full, clear, 10 and exact description of the same, and which said drawings constitute part of this specification, and represent, in—

Figure 1, a broken view, in front elevation, showing the application of two of my improved locking devices to the lower ends of 15 the two busks of a corset; Fig. 2, a detached view, in front elevation, of the device.

My invention relates to an improvement in locking devices for that class of corsets, the 20 fastening devices whereof comprise headed studs and hooks adapted to be engaged therewith, the object of my present invention being to produce, at a very lowcost for manufacture, a simple, convenient and effective locking 25 device, adapted to be transferred from one corset to another and designed to prevent the hooks of their fastening devices from being disengaged from the headed studs thereof.

With these ends in view, my invention consists 30 in certain details of construction and combinations of parts as will be hereinafter described and pointed out in the claim.

In carrying out my invention, I form in dies 35 from a single piece of sheet-metal, a small plate, comprising a handle-end A and a locking-end A', the former being adapted in size and shape to be conveniently grasped by the thumb and fingers for manipulating the device, and the latter containing a central, lon- 40 gitudinally-arranged, elongated slot a uniform in width throughout its length and a clearance notch a' offsetting laterally as shown from the inner end of the inner side wall of the said slot.

It is apparent that the particular contour 45 of the locking device may be widely varied in detail, but in any form it will comprise a handle-end and a locking-end, the former being adapted to be grasped by the thumb and 50 fingers and the latter containing a locking slot and a clearance notch.

My improved locking device is designed to

be used with a corset having one of its busks, B, furnished with headed studs C, and the other of its busks, B', furnished with sheet- 55 metal hooks C, containing slots or openings, the inner ends of which are enlarged to permit the hooks to be engaged with the studs.

I do not, however, limit the use of my improved locking device to a fastening device 60 consisting of headed studs and hooks of the form shown, for the hooks might be changed in form or construction without interfering with the use of my improvement.

I may employ one, or more than one, of my 65 improved locking devices in each corset, it being particularly desired that the hook and stud at the lower ends of the busks should be provided with a fastening device, for the particular hook and stud mentioned are more 70 likely than any others to become unfastened, allowing the lower ends of the busks to separate, which not only impairs the fit and convenience of the corset but also endangers the busks, as when so separated they are very 75 likely to be bent too far and broken.

My design is that my improved locking devices shall be made and supplied to the trade independently of the corsets. On account of 80 being independent thereof, they may be transferred from one corset to another, as desired. In applying the locking device, it is presented to the headed stud with which it is desired to engage it in the inclined position in which the upper locking device of the two shown in 85 Fig. 1 of the drawings is represented, the hook having been previously engaged with the stud in the usual manner. In this way the clearance notch is passed under the head and over the shank of the stud, the head of the stud 90 being thus allowed to pass through the slot to permit the device to be drawn down into its normal pendent position, in which it is supported by gravity and in which it is retained upon the stud by the head thereof. Obvi- 95 ously, as long as the fastening device is retained upon the head of the stud the hook cannot be disengaged therefrom. If the device should be lifted in any manner so as to cause the stud to move into the lower end of the slot or to the point therein opposite the clearance notch, the device will not on that account be disengaged, because, to effect that result, it must be canted or inclined, and in

that position drawn away from the head of the stud.

I am aware that a slotted sheet-metal locking device for locking the fastening devices of a corset against disengagement is old, and I do not, therefore, claim such a construction broadly.

I am further aware that a fastening device having an elongated slot constructed with an offset or clearance notch is old, and I do not claim such a construction broadly.

Having fully described my invention, what I claim as new, and desire to secure by Letters Patent is—

15 In a corset, the combination with the busks thereof, of headed studs and laterally arranged sheet-metal hooks respectively applied to the said busks, and the said hooks having openings enlarged at their inner ends
20 to receive the said headed studs; and a vertically arranged pendent locking device consisting solely of a vertically elongated single

piece of sheet-metal of which the upper end forms a locking-end, and the lower end a handle-end, the former having formed in it a longitudinally arranged vertical slot, uniform in width throughout its length, and also having formed in it near its lower end a single clearance notch, offsetting laterally from one of the side walls of the said slot, and combining with the slot to form a sufficient clearance opening for the application of the device to, and its removal from one of the headed studs when the device is in a tilted or inclined position with respect to the head of the stud, substantially as described.

In testimony whereof I have signed this specification in the presence of two subscribing witnesses.

SARAH J. ROOT.
